UNITED STATES PATENT OFFICE.

EUGENE GENGENBACH, OF NEW YORK, N. Y.

HOUSING FOR ELECTROMAGNETS.

Specification of Letters Patent.

Patented May 26, 1914.

1,098,246.

Application filed January 11, 1913. Serial No. 741,395.

To all whom it may concern:

Be it known that I, EUGENE GENGENBACH, a citizen of the United States, and a resident of the city of New York, borough of Manhattan, in the county and State of New York, have invented a new and Improved Housing for Electromagnets, of which the following is a full, clear, and exact description.

10 This invention relates generally to housings for electro-magnets, and is more particularly directed to an iron-clad construction, the results of which contemplate not only greater protection of the winding of the electro-magnet, but also provide for greater efficiency of operation.

The principal object of the invention is the production of housings for electro-magnets adapted to be made from sheet metal 20 which may be bent to suitable forms, and characterized by certain portions coöperating with the armature of the electro-magnet, whereby an inexpensive but efficient mechanism is provided.

25 Reference is to be had to the accompanying drawings forming a part of this specification, in which like characters of reference indicate corresponding parts in all the views, and in which—

30 Figure 1 is a perspective view of one form of the invention; Fig. 2 is a vertical sectional view thereof; Fig. 3 is a horizontal sectional view thereof; Fig. 4 is a developed surface of the blank from which the housing is made; Fig. 5 is a developed surface of the blank from which the armature is made; while Fig. 6 is a detail sectional view showing the manner of pivotally mounting the armature in position.

40 The electro-magnet proper comprises the usual core 1 and the winding 2 carried thereon, the upper end of the core being provided with the usual pole piece or face 3, the lower end of the core being extended for a suitable distance, forming a pole face 4.

45 The electro-magnet is adapted to be enclosed in a sheet metal casing or housing, the particular shape of the blank from which such housing is made being set forth in Fig. 4. The blank presents the appearance of a cross made up of the main longitudinally extending portion 5^a having the offsets 6^a—6^b. Midway of the said offsets an opening 7 is provided, into which the lower pole piece 4 of the core is adapted to be secured, whereby the electro-magnet is made

rigid with the housing, as shown particularly in Fig. 2. The middle part 5^b of the longitudinally extending portion of the blank is provided with openings 8—9, and beyond the said openings are other openings 8^a—9^b adapted to register with the said openings 8—9 when the said longitudinally extending portion is bent along the lines x—y. The outer ends of the said longitudinally extending portion are again bent along the lines m—n, whereby flanges 10—11 are formed (Fig. 3) having the openings 8—9 therein, whereby the housing may be secured in position as desired. The outer ends of the longitudinally extending portion of the blank form sides 12—13 of the housing. These sides 12—13 adjacent their outer edges are bent along the lines o—p in order to form overhanging shoulders 14—15 which lie closely adjacent the top of the winding 2 and serve to maintain the winding securely in the housing. The magnet winding 2 is in the form of a spool assembled on the core 1, and to hold the spool in place the flanges 14—15 are provided. Referring particularly to Fig. 4 it will be noted that opposite sides of the said outer ends or sides 12—13 are provided with lugs 16—17 adapted to be entered into openings 18—19 formed in the said offsets 6^a—6^b when the said offsets are bent upwardly along the lines r—s, the result being the box-like structure shown particularly in Fig. 3. These offsets 6^a—6^b are also bent adjacent their outer edge portions, as along the lines t—u, in order to form overhanging ends 20—21 similar in shape and function to the overturned edge portions 14—15.

50 Pivotedly mounted on top of the housing and adjacent the core of the electro-magnet is the armature 22, the blank from which it is made being shown particularly in Fig. 5. The blank comprises a central body portion 25^a having the oppositely extending and narrowed portions 26^a—26^b, each of which is slotted in order to form tongues 27—28, opposite corners of the body portion 25^a being provided with ears 29 having openings 30 therein. As shown particularly in Figs. 1 and 6, these ears 29 are bent downwardly closely adjacent the opposite sides of the housing, the material forming the said opposite sides being punched outwardly for a suitable distance in order to form teeth 31 adapted to enter the said openings 30, whereby a pivotal mounting is provided.

Referring particularly to Figs. 1 and 2 it will be noted that the tongue 28 is bent downwardly beneath the body portion 25^a and is adapted to come adjacent a contact point 32 carried on an adjustable screw 33 which is insulatingly mounted on a support 34. This support 34 is formed integrally with the housing blank, and is indicated in Fig. 4 as lying adjacent the line of bending 10 y, said support being provided with an opening 35 adapted to receive the said adjustable screw 33.

In order to maintain the end of the tongue or movable contact 28 in engagement 15 with the contact point 32 a helical spring 36 is employed, one end of which engages the outer end of the armature 22, the other end of which is secured in the said support 34. As a further means of determining the 20 movement of the armature relatively to the electro-magnet the tongue 27, formed in the blank from which the armature is made, may be bent downwardly into the position shown in Fig. 2, and may be entered into 25 the opening 37 formed in the side 12 of the housing, the location of the said opening being shown in Fig. 4. The upper end of the opening 37 forms a stop or abutment with which the tongue 27 engages to limit the 30 movement of the armature away from the core under the tension of the spring 36.

Any or all of the sides may be provided with openings 38, if so desired, adapted to conduct the wires 39 leading from the electro-magnet exteriorly of the housing, where 35 they may be secured to suitable studs 40 carried on an insulating plate 41 fixed to the side of the housing in any desirable manner, as by means of lugs 42 formed integrally therewith. On this same insulating element 40 41 are other studs 43 which may be integral with the first studs 40, and which serve as a connection for the circuit wires leading to the electro-magnet.

If so desired, the interior of the housing 45 may be lined with any suitable material, such as insulation or waterproof material. The housing illustrated and described is merely one of many forms which the idea 50 may assume, the use of such a housing not only preventing injury to the winding of the electro-magnet, but at the same time increasing the efficiency of the said magnet, due to the fact that an iron circuit is provided for the magnetic field from the lower 55 end of the core to a location adjacent the upper end of the said core. The structure is exceedingly simple and may be formed by stamping, the subsequent act of bending being adapted to be performed by suitable dies, all of which tends to economical construction.

Having thus described my invention, what I claim as new and desire to secure by Letters Patent is:—

1. A housing for an electro-magnet comprising a single piece structure consisting of a base and sides rising therefrom, certain of the sides being connected with the base by doubled portions forming laterally-extending flanges at and in the same plane with the base, said flanges having fastening receiving apertures, whereby the housing may be secured to a support. 70

2. A housing for an electro-magnet comprising a single piece structure consisting of a base and sides rising therefrom, certain of the sides being connected with the base by doubled portions forming laterally-extending flanges at the base, whereby the housing may be secured to a support, in combination with a core fastened to the base, a magnet assembled on the core, and internal flanges on the sides of the housing to engage the electro-magnet and hold the same in place. 75 80

3. The combination of a housing, an electro-magnet therein, an armature pivoted on the housing, a tongue on the armature, an opening in the side of the housing forming an abutment with which the tongue engages 90 for limiting the movement of the armature away from the magnet, and a spring operating on the armature to oppose the movement of the same toward the magnet. 90

4. A housing for an electro-magnet comprising a sheet metal structure consisting of a base and four sides, two of the sides being directly connected with the base and the other two sides being connected with the base by lateral extensions, internal 100 flanges on the said sides co-operating to form an internal flange extending entirely around the structure, an electro-magnet mounted in the structure and of such axial length as to engage under the flanges with the magnet 105 resting on the said base, an armature secured to the said structure and forming a cover for the same over the magnet, a circuit make-and-break device consisting of members on the said structure and armature 110 respectively, and a spring connected with the said structure and armature for holding the said members in engagement. 110

5. A housing for electro-magnets comprising a casing open at the top, an armature pivoted on the casing and consisting of a plate-like body having oppositely-projecting extensions, tongues struck out from the extensions, an abutment on the casing with which one tongue engages for limiting the 115 movement of the armature, a fixed contact on the casing for engagement with the other tongue to form a circuit make-and-break device, an electro-magnet in the casing, and a spring connected with the armature to oppose the movement thereof by the electro-magnet. 120 125

6. The combination of a housing consisting of a base and sides, said base extending outwardly from the sides, a tongue struck 130

from the base extension and forming a fixed member of a circuit make-and-break device, an armature on the said housing and having a member forming a movable contact cooperating with the first mentioned member, an electro-magnet in the housing for actuating the armature in one direction, and a spring connected with the armature and with the first mentioned member to oppose

the action of the armature by the electro- 1
magnet.

In testimony whereof I have signed my name to this specification in the presence of two subscribing witnesses.

EUGENE GENGENBACH.
